SWITCH DEVICE

BACKGROUND

1. Field

The following description relates to a switch device that switches contacts with a snap action mechanism.

2. Description of Related Art

Japanese Laid-Open Patent Publication No. 2010-73662 discloses a known switch device including a snap action mechanism that is actuated when pressed by an operation member. The switch device of Japanese Laid-Open Patent Publication No. 2010-73662 includes a housing, the operation member, a fixed contact, a movable contact, and the snap action mechanism. The snap action mechanism drives the movable contact when the operation member is pressed to a predetermined position.

SUMMARY

When a contact is mounted on a board in such a type of switch device, it is desired that the contact be planar-mounted to facilitate mounting on the board. In this case, for example, a portion of the contact connected to the board, namely, a connection pin, needs to be bent parallel to a mounting surface of the board.

When, for example, bending the connection pin of the contact after the contact is coupled to the case of the switch device, the connection pin will be difficult to bend. When bending the connection pin of the contact before the contact is coupled to the case, bending adjustments will be easy to make.

When bending the connection pin in advance, however, the bent connection pin may interfere with the case.

This Summary is provided to introduce a selection of concepts in a simplified form that are further described below in the Detailed Description. This Summary is not intended to identify key features or essential features of the claimed subject matter, nor is it intended to be used as an aid in determining the scope of the claimed subject matter.

In one general aspect, a switch device includes a movable terminal including a snap action mechanism that bends a spring when a user moves an operating portion, a first fixed terminal that contacts the movable terminal when the spring is not bent, a second fixed terminal that contacts the movable terminal when the operating portion is moved by a specified amount to bend the spring, and a housing that accommodates at least the first fixed terminal. The first fixed terminal includes a first fixed terminal body that contacts the movable terminal, and a first fixed terminal connection pin bent sideward from the first fixed terminal body and mounted on a board. The housing includes a groove portion that allows for passage of the first fixed terminal connection pin.

Other features and aspects will be apparent from the following detailed description, the drawings, and the claims.

BRIEF DESCRIPTION OF THE DRAWINGS

FIG. 1 is a perspective view of a switch unit according to one embodiment.

FIG. 2 is a perspective view of the switch device.

FIG. 3 is an exploded perspective view of the switch device.

2

FIG. 4A is a diagram showing an operation of the switch device.

FIG. 4B is a diagram showing an operation of the switch device.

5 FIG. 5 is a perspective view showing how a first fixed terminal is coupled to a case.

FIG. 6 is a side view of the switch device.

FIG. 7 is a cross-sectional view taken along line VII-VII in FIG. 6.

10 FIG. 8 is a cross-sectional view taken along line VIII-VIII in FIG. 2.

FIG. 9 is a cross-sectional view taken along line IX-IX in FIG. 6.

15 FIG. 10 is a partially enlarged perspective view of the switch device.

FIG. 11 is a perspective view showing the inside of the case where a fixed contact is arranged.

20 FIG. 12 is a perspective view showing the inside of the case where the fixed contact is arranged.

FIG. 13 is a diagram showing the electric configuration of a switch unit.

FIG. 14 is a table for determining the state of contacts.

Throughout the drawings and the detailed description, the same reference numerals refer to the same elements. The drawings may not be to scale, and the relative size, proportions, and depiction of elements in the drawings may be exaggerated for clarity, illustration, and convenience.

DETAILED DESCRIPTION

This description provides a comprehensive understanding of the methods, apparatuses, and/or systems described. Modifications and equivalents of the methods, apparatuses, and/or systems described are apparent to one of ordinary skill in the art. Sequences of operations are exemplary, and may be changed as apparent to one of ordinary skill in the art, with the exception of operations necessarily occurring in a certain order. Descriptions of functions and constructions that are well known to one of ordinary skill in the art may be omitted.

Exemplary embodiments may have different forms, and are not limited to the examples described. However, the examples described are thorough and complete, and convey 45 the full scope of the disclosure to one of ordinary skill in the art.

In this specification, “at least one of A and B” should be understood to mean “only A, only B, or both A and B.”

One embodiment of the present disclosure will now be 50 described.

Switch Unit 1

As shown in FIG. 1, a switch unit 1 is, for example, an electric parking brake switch 2 that is manually moved to electrically activate and deactivate the parking brake of a vehicle. The switch unit 1 is located, for example, inside the passenger compartment (near driver seat) of the vehicle.

The switch unit 1 includes a frame 3 and an operating portion 4 movably attached to the frame 3. The operating portion 4 attached to the frame 3 is rotatable about a shaft 5 arranged in, for example, the frame 3 or the operating portion 4. The operating portion 4 can be rotated in two directions (first operation direction R1, second operation direction R2) about the axis La of the shaft 5. The operating portion 4 is rotated, for example, in the first operation direction R1 or the second operation direction R2, from a neutral position. The operating portion 4 is, for example, of a momentary type in which the operating portion 4 auto-

matically returns to the neutral position when a user releases the operating portion 4 after rotating it from the neutral position.

To activate the parking brake, for example, the user moves the operating portion 4 in the first operation direction R1 from the neutral position while depressing the braking pedal. Movement of the operating portion 4 in the first operation direction R1, for example, raises the operating portion 4. In this case, the parking brake is activated when the operating portion 4 is moved to a first operation position (electric parking brake activation position) at the limit end in the first operation direction R1.

To deactivate the parking brake, for example, the user moves the operating portion 4 in the second operation direction R2 from the neutral position while depressing the braking pedal. Movement of the operating portion 4 in the second operation direction R2, for example, lowers the operating portion 4. In this case, the parking brake is deactivated when the operating portion 4 is moved to a second operation position (electric parking brake deactivation position) at the limit end in the second operation direction R2. The parking brake may be automatically deactivated when, for example, a shifter of the vehicle is set to the drive position and the vehicle starts to travel.

Switch Device 8

As shown in FIG. 2, the switch unit 1 includes switch devices 8 that detect movement of the operating portion 4. The switch devices 8 of the present example include a first switch device 8a that detects movement of the operating portion 4 in the first operation direction R1 and a second switch device 8b that detects movement of the operating portion 4 in the second operation direction R2. The two switch devices 8 are, for example, arranged next to each other. The switch devices 8 basically have identical structures. The structure of the switch devices 8 will now be described.

The switch device 8 includes a housing 9 that accommodates device components. The housing 9 is substantially a rectangular parallelepiped. The housing 9 includes a case 11, having an opening 10, and a cover 12 that closes the opening 10. The case 11 is, for example, an insulator that insulates electric components of the switch device 8. The case 11 is box-shaped and has a closed end and an opposite end (upper end in present example) that is closer to the cover 12 and includes the opening 10. In one example, the case 11, which is box-shaped, includes a bottom surface that is closed and an upper surface that is open by the opening 10. The case 11 includes two opposing side walls 13. The cover 12 is fixed to the case 11 through, for example, welding. The welding may be laser welding.

As shown in FIG. 3, a leg 14 extends from each of the four corners of the rear surface of the cover 12. The four corners in the open end of the case 11 each include an engagement portion 15 paired with a corresponding one of the legs 14 of the cover 12. The cover 12 is coupled to the case 11 so that the legs 14 are engaged with the corresponding engagement portions 15 of the case 11.

Each switch device 8 includes a movable terminal 18, a first fixed terminal 19, and a second fixed terminal 20. The movable terminal 18 is moved when the user moves the operating portion 4. Further, the movable terminal 18 selectively contacts the first fixed terminal 19 and the second fixed terminal 20. The movable terminal 18 includes a movable terminal body 18a and movable terminal connection pins 18b mounted on a board 21. Two movable terminal connection pins 18b are respectively arranged, for example,

at the two sides of the switch device 8 in the width direction (device width direction: Y-axis direction in FIG. 3).

A linking portion 18c, used when forming the movable terminal 18 during a pressing process, is arranged adjacent to each movable terminal connection pin 18b. The linking portion 18c does not have the functionality of a terminal and may be omitted.

The movable terminal connection pins 18b extend out of the case 11 through holes 11a formed in the side walls 13 of the case 11. The linking portions 18c extend out of the case 11 through holes 11b formed in the side walls 13 of the case 11.

The movable terminal 18 has a snap action mechanism 23 that bends a spring 22 when the user moves the operating portion 4. The proximal end of the spring 22 is fixed to two engaging portions 24, 25 arranged on the movable terminal body 18a. The distal end of the spring 22 includes a movable contact 26 of the movable terminal 18. The movable contact 26 is, for example, a rivet. The rivet of the present example undergoes, for example, a swaging process for attachment to the spring 22. The rivet has the minimum diameter that allows for swaging.

The spring 22 includes a tensile portion 27 that applies tensile force to the proximal end of the spring 22 and a compression portion 28 that applies reaction force in a direction opposite to the direction of tensile force. The proximal end of the tensile portion 27 is engaged with the engaging portion 24, which is located toward one end of the case 11. The proximal end of the compression portion 28 is engaged with the engaging portion 25 which is located at the middle part of the case 11.

A pressing portion 31 moved in cooperation with the operating portion 4 is arranged on the proximal end of the tensile portion 27 opposing the operating portion 4. The pressing portion 31 includes a head 31a that is exposed to the outside of the housing 9 through a hole 32 extending through the cover 12. The pressing portion 31 is moved back and forth in the height direction (device height direction: Z-axis direction in FIG. 3) of the switch device 8. The spring 22 bends when the pressed amount of the pressing portion 31 reaches a specified amount.

The first fixed terminal 19 includes a first fixed terminal body 19a, which contacts the movable terminal 18, and first fixed terminal connection pins 19b, which are arranged at the ends of the first fixed terminal body 19a. The first fixed terminal 19 is located closer to the cover 12 than the movable terminal 18. The first fixed terminal body 19a is, for example, C-shaped. The first fixed terminal body 19a is located at a position opposed to the movable terminal 18.

The first fixed terminal connection pins 19b are arranged at, for example, the two ends of the first fixed terminal body 19a. The first fixed terminal connection pins 19b are pin-shaped and have a narrower width than the first fixed terminal body 19a. The first fixed terminal connection pins 19b extend out of the housing 9 (case 11 in present example) through groove portions 33 formed in the side walls 13 of the case 11. The first fixed terminal connection pins 19b are mounted on the board 21.

The second fixed terminal 20 includes a second fixed terminal body 20a that contacts the movable terminal 18 and second fixed terminal connection pins 20b arranged at the ends of the second fixed terminal body 20a. The second fixed terminal 20 is located closer to the bottom of the case 11 than the movable terminal 18. The second fixed terminal body 20a is located at a position opposed to the movable terminal 18. The second fixed terminal connection pins 20b are arranged at, for example, two opposite ends of the

second fixed terminal body 20a. The second fixed terminal connection pins 20b are mounted on the board 21.

A linking portion 20c, used when forming the second fixed terminal 20 during a pressing process, is arranged adjacent to each second fixed terminal connection pin 20b. The linking portion 20c does not have the functionality of a terminal and may be omitted.

The second fixed terminal connection pins 20b extend out of the case 11 through holes 11d formed in the side walls 13 of the case 11. The linking portions 20c extend out of the case 11 through holes 11e formed in the side walls 13 of the case 11.

The movable terminal 18 (excluding spring 22) and the second fixed terminal 20 may be fixed the case 11 from the lower side. Alternatively, the movable terminal 18 (excluding spring 22) and the second fixed terminal 20 may be insert-molded to the case 11.

Action for Switching Contacts in Switch Device 8

As shown in FIG. 4A, when the operating portion 4 is not moved and located at the neutral position, the spring 22 of the snap action mechanism 23 is not bent. In this case, the resultant force of the tensile force of the tensile portion 27 and the reaction force of the compression portion 28 in the spring 22 acts upward (toward first fixed terminal 19) on the movable contact 26. Thus, the movable contact 26 of the movable terminal 18 contacts the first fixed terminal 19.

As shown in FIG. 4B, when the operating portion 4 is rotated in the first operation direction R1 (second operation direction R2) thereby pressing the pressing portion 31 so that the operating portion 4 is moved for the specified moved amount, the resultant force of the tensile force and the reaction force acts downward (toward second fixed terminal on the movable contact 26. Thus, the movable contact 26 moves away from the first fixed terminal 19 and contacts the second fixed terminal 20. That is, the connection of the movable terminal 18 switches from the first fixed terminal 19 to the second fixed terminal 20.

When the operating portion 4 is released, the spring 22 bends back to its original state. Thus, the movable contact 26 returns to the state contacting the first fixed terminal 19. In this manner, the movable contact 26 selectively contacts the first fixed terminal 19 and the second fixed terminal 20 in accordance with the moved amount of the operating portion 4.

Structure of First Fixed Terminal 19

As shown in FIG. 3, the first fixed terminal 19 of the present example is separate from, for example, the cover 12. The first fixed terminal 19 is positioned in the case 11 by the cover 12 when, for example, the opening 10 is closed by the cover 12. Specifically, the first fixed terminal 19 is pressed from above by the cover 12 and positioned when coupled to the case 11.

The first fixed terminal connection pins 19b are bent in advance in the direction parallel to a mounting surface 34 of the board 21 before the first fixed terminal 19 is coupled to the case 11. In this manner, the first fixed terminal connection pins 19b are bent in advance. The first fixed terminal connection pins 19b of the present example extend in the horizontal direction (X-Y plane direction in FIG. 3) on the mounting surface 34 of the board 21. Thus, the first fixed terminal connection pins 19b are bent in advance when the first fixed terminal 19 is coupled and fixed to the case 11.

Structure of Groove Portions 33

As shown in FIGS. 5 and 6, the groove portions 33 are formed to allow for passage of the first fixed terminal connection pins 19b. When coupling the first fixed terminal 19 to the case 11, the groove portions 33 allow for passage

of the first fixed terminal connection pins 19b. The groove portions 33 of the present example are formed in the two side walls 13. The groove portions 33 each include a guide groove 37 that allows for passage of the corresponding first fixed terminal connection pin 19b when coupling the first fixed terminal 19 to the case 11. The guide groove 37 has, for example, a groove width that narrows in the direction (direction A1 indicated by arrow in FIG. 6) the first fixed terminal 19 is coupled to the case 11. In this manner, at least part of the groove portion 33 is narrowed.

The groove portion 33 includes a cutout groove 38 that provides space for the first fixed terminal connection pin 19b when coupling of the first fixed terminal 19 to the case 11 is completed. The cutout groove 38 is continuous with, for example, the lower end of the guide groove 37. The groove portion 33 (guide groove 37 and cutout groove 38) extends from the upper end to the lower end in the corresponding side wall 13 of the case 11.

Measures Against Entry of Foreign Material from Groove Portion 33

As shown in FIG. 6, the cover 12 includes projecting walls 39 fitted into at least part of the groove portions 33 when the cover 12 is coupled to the case 11. In one example, each projecting wall 39 is fitted into the corresponding groove portion 33 from the upper end to an intermediate portion in the depth direction of the groove portion 33, for example, to the lower end of the guide groove 37. The projecting wall 39 is formed to project from a rear surface edge of the cover 12 toward the case 11. The two projecting walls 39 are each paired with the corresponding groove portion 33. The projecting walls 39 are each fitted into at least part of the corresponding groove portion 33 to limit entry of foreign material from the groove portions 33 into the housing 9. Each projecting wall 39 of the present example is formed to fit into the guide groove 37 of the corresponding groove portion 33. In this case, the projecting wall 39 is narrowed in conformance with the shape of the guide groove 37.

As shown in FIG. 7, the switch device 8 includes two restriction walls 40 respectively arranged at the inner sides of the groove portions 33 in the housing 9. The two restriction walls 40 of the present example are respectively paired with the two groove portions 33 in the case 11. The restriction walls 40 of the present example each project from the case 11 to, for example, partially cover the inner side of the lower end of the corresponding guide groove 37 and entirely cover the corresponding cutout groove 38. The restriction wall 40 partitions each groove portion 33 (guide groove 37, cutout groove 38) from the inside of the case 11 so that foreign material from the groove portion 33 does not enter the housing 9 (case 11).

Arrangement of Connection Pin Group

As shown in FIG. 6, the movable terminal connection pin 18b and the second fixed terminal connection pin 20b are arranged to extend in the same direction (horizontal direction) as the first fixed terminal connection pin 19b. In other words, the movable terminal connection pin 18b and the second fixed terminal connection pin 20b extend in the same projection direction as the bent first fixed terminal connection pin 19b. This allows for surface mounting when the switch device 8 is mounted on the board 21.

In the present example, the linking portions 18c, 20c are also arranged to extend in the same direction (horizontal direction) as the first fixed terminal connection pin 19b. Thus, the movable terminal connection pin 18b, the first

fixed terminal connection pin **19b**, the second fixed terminal connection pin **20b**, and the linking portions **18c**, **20c** are all arranged on the same plane.

Press-Fitting Structure of First Fixed Terminal **19**

As shown in FIG. 8, the switch device **8** includes a press-fitting mechanism **43** that temporarily fixes the first fixed terminal **19** to the housing **9** (case **11** in present example) through press-fitting. The press-fitting mechanism **43** of the present example includes a press-fitting portion **44** formed in the groove portion **33** of the case **11**. The press-fitting portion **44** of the present example is arranged in the groove portion **33** next to the guide groove **37**. In one example, the press-fitting portion **44** is arranged in the side wall **13** of the case **11** where the groove portion **33** is defined, for example, inside the case **11** at the part where the guide groove **37** is defined. The press-fitting portion **44** is a recessed portion into which a proximal end **19c** of the first fixed terminal body **19a** is pressed. The press-fitting portion **44** includes two first catches **45** that are opposed to each other in the recessed portion. Each first catch **45** has a predetermined bulging shape.

The press-fitting mechanism **43** includes two second catches **46** at the proximal end **19c** of the first fixed terminal **19**. The second catches **46** are arranged on the side surfaces of the proximal end **19c** and have bulging shapes so as to be bulged alternately with the corresponding first catches **45**. The press-fitting mechanism **43** temporarily fixes the first fixed terminal **19** to the case **11** by press-fitting the proximal ends **19c** of the first fixed terminal body **19a** to the press-fitting portions **44** of the case **11**. Thus, when the first catches **45** are press-fitted to the second catches **46** of the case **11**, the first fixed terminal **19** is temporarily fixed to the case **11**.

Temporary Holding of Cover **12** on Case **11**

As shown in FIG. 9, the switch device **8** includes temporary holding portions **48** used to temporarily fix the cover **12**, which is coupled to the case **11** to close the opening to the case **11**. The temporary holding portions **48** of the present example each include compressible ribs **49** formed on, for example, the side surfaces of the engagement portion of the case **11**.

The compressible ribs **49** of the present example are arranged to set the reference position of the case **11** in the device width direction (Y-axis direction in FIG. 9) and the device longitudinal direction (X-axis direction in FIG. 9). Specifically, the compressible ribs **49** include two first compressible ribs **49a** that set the reference position of the case **11** in the device width direction and two second compressible ribs **49b** that set the reference position of the case **11** in the device longitudinal direction. In other words, the compressible ribs **49** include the two first compressible ribs **49a** that position the case **11** at the reference position in the device width direction and the two second compressible ribs **49b** that position the case **11** at the reference position in the device longitudinal direction. The cover **12** is temporarily fixed to the case **11** by the compressible ribs **49** and then permanently fixed to the case **11** by welding (for example, laser welding).

Pressing of First Fixed Terminal **19** by Cover **12**

As shown in FIG. 10, the cover **12** has a rear surface including compressible ribs to press the first fixed terminal **19** from above when the cover **12** is temporarily fixed to the case **11**. In the present example, three ribs **50** are arranged on the cover **12**. The ribs **50** press the first fixed terminal **19** from above when the cover **12** is temporarily fixed to the case **11**. The ribs **50**, for example, hold the first fixed terminal **19** in place until the cover **12** is welded to the case **11**.

Detail of Shape of Second Fixed Terminal **20**

As shown in FIGS. 11 and 12, the second fixed terminal **20** includes a fixed contact **53**, which is a portion that contacts the movable terminal **18**, formed by processing part **5** of the second fixed terminal **20**. The second fixed terminal **20** contacts the movable contact **26** of the movable terminal **18** at the fixed contact **53**. The fixed contact **53** is formed by cutting and bending the base material of the second fixed terminal **20**.

As shown in FIG. 11, the fixed contact **53** is shaped to project in a bulging manner toward the movable terminal **18** from a base portion **54** of the second fixed terminal body **20a**. The fixed contact **53** is shaped to be an arch as viewed from the side (Y-axis direction in FIG. 11). The second fixed terminal **20** includes a cutout hole **55** beneath the fixed contact **53**.

Electric Structure of Switch Unit **1**

As shown in FIG. 13, the switch unit **1** includes a controller **80** that detects movement of the operating portion **4** from an output of the switch device **8**. The controller **80** is connected to the first switch device **8a** that detects movement of the operating portion **4** in the first operation direction **R1** and the second switch device **8b** that detects movement of the operating portion **4** in the second operation direction **R2**. The controller **80** of the present example is connected to the first switch device **8a** and the second switch device **8b** by first to fourth ports **P1** to **P4**.

Specifically, in the first switch device **8a**, the movable terminal connection pin **18b** is connected to first port **P1**, the first fixed terminal connection pin **19b** is connected to fourth port **P4**, and the second fixed terminal connection pin **20b** is connected to second port **P2**. In the second switch device **8b**, the movable terminal connection pin **18b** is connected to third port **P3**, the first fixed terminal connection pin **19b** is connected to second port **P2**, and the second fixed terminal connection pin **20b** is connected to fourth port **P4**.

As shown in FIG. 14, when the operating portion **4** is in the neutral position, the movable terminals **18** of the first switch device **8a** and the second switch device **8b** are connected to the corresponding first fixed terminals **19**. Thus, first port **P1** is connected to fourth port **P4**, and second port **P2** is connected to third port **P3**. When the controller **80** detects this connection state, the controller **80** determines that the operating portion **4** is in the neutral position.

When the operating portion **4** is moved to the first operation position in the first operation direction **R1**, the connection of the movable terminal **18** is switched from the first fixed terminal **19** to the second fixed terminal **20** only in the first switch device **8a**. Thus, movement of the operating portion **4** to the first operation position connects first port **P1**, second port **P2**, and third port **P3**. When the controller **80** detects this connection state, the controller **80** determines that the operating portion **4** has been moved to the first operation position. Thus, the movement is detected as activation of the electric parking brake switch **2**.

When the operating portion **4** is moved to the second operation position in the second operation direction **R2**, the connection of the movable terminal **18** is switched from the first fixed terminal **19** to the second fixed terminal **20** only in the second switch device **8b**. Thus, movement of the operating portion **4** to the second operation position connects first port **P1**, third port **P3**, and fourth port **P4**. When the controller **80** detects this connection state, the controller **80** determines that the operating portion **4** has been moved to the second operation position. Thus, the movement is detected as deactivation of the electric parking brake switch **2**.

Operation of Embodiment

The operation of the switch device **8** in the present embodiment will now be described.

As shown in FIG. 5, the distal ends of the first fixed terminal connection pins **19b** are bent in advance when the first fixed terminal **19** is coupled to the case **11**. Thus, bending adjustments can be made more readily than when the first fixed terminal connection pins **19b** are bent after the first fixed terminal **19** is coupled to the case **11**. Further, the first fixed terminal connection pins **19b** are bent with higher accuracy when bent in advance. This improves the coplanarity accuracy when mounted on the board **21**.

The first fixed terminal connection pins **19b**, which are bent in advance, extend sideward from the first fixed terminal body **19a**. Thus, the case **11** needs passages that allow for passage of the first fixed terminal connection pins **19b** without interfering with the first fixed terminal connection pins **19b**. In the present example, the side walls **13** of the case **11** include the groove portions **33** (specifically, guide grooves **37**) so that the first fixed terminal connection pins **19b** are allowed to pass through the side walls **13**.

As shown in FIG. 6, the cover **12** includes the projecting wall **39** to close the groove portion **33**. When the side wall **13** of the case **11** includes the groove portion **33**, foreign material may enter the case **11** from the groove portion **33**. In the present example, the cover **12** includes the projecting wall **39** to close the groove portion **33**. This limits entry of foreign material from the groove portion **33**.

As shown in FIG. 7, the restriction walls **40** are arranged at the inner sides of the groove portions **33** in the case **11**. Thus, the restriction walls **40** limit the entry of foreign material from the groove portions **33** into the case **11**. In particular, the present example limits the entry of foreign material from each groove portion **33** into the case **11** in cooperation with three corresponding walls including the projecting wall **39** of the cover **12**, the proximal end **19c** of the first fixed terminal **19**, and the restriction wall **40** in the case **11**. This structure further limits the entry of foreign material into the case **11**.

As shown in FIGS. 3 and 6, the extension direction of the pin group including the movable terminal connection pins **18b**, the first fixed terminal connection pins **19b**, and the second fixed terminal connection pins **20b** is parallel to the mounting surface **34** of the board **21**. Thus, the switch device **8** is mounted on the board **21** through surface mounting rather than through-hole mounting. This improves the degree of freedom for mounting and allows the switch device **8** to be reduced in size.

Advantages of Embodiment

The switch device **8** in the above embodiment has the following advantages.

(1) The switch device **8** includes the housing **9**, the movable terminal **18**, the first fixed terminal **19**, and the second fixed terminal **20**. The housing **9** accommodates at least the first fixed terminal **19**. The movable terminal **18** has the snap action mechanism **23** that bends the spring **22** when the user moves the operating portion **4**. The movable terminal **18** contacts the first fixed terminal **19** when the spring **22** is not bent. The movable terminal **18** contacts the second fixed terminal **20** when the operating portion **4** is moved by a specified amount thereby bending the spring **22**. The first fixed terminal **19** includes the first fixed terminal body **19a**, which contacts the movable terminal **18**, and the first fixed

terminal connection pins **19b**, which are bent sideward from the first fixed terminal body **19a** and mounted on the board **21**. The housing **9** includes the groove portions **33** that allow for passage of the first fixed terminal connection pins **19b**.

With this structure, since the first fixed terminal connection pins **19b** are bent sideward, the first fixed terminal **19** can be planar-mounted on the mounting surface **34** of the board **21**. The case **11** includes the groove portions **33** allowing for passage of the first fixed terminal connection pins **19b** when the first fixed terminal **19** is coupled to the case **11**. Thus, even when the first fixed terminal connection pins **19b** are bent in advance before coupling in order to facilitate bending of the first fixed terminal connection pins **19b**, the case **11** will not interfere with the first fixed terminal connection pins **19b** when the first fixed terminal **19** is being coupled to the case **11**. This allows bending to be performed in advance, thereby facilitating manufacturing of the switch device **8**.

(2) The switch device **8** includes the case **11**, which has the opening **10**, and the cover **12**, which closes the opening **10** and positions the first fixed terminal **19**. The cover **12** includes the projecting walls **39** fitted into at least part of the groove portions **33** when the cover **12** is coupled to the case **11**. With this structure, the projecting walls **39** cover the groove portions **33** and limit entry of foreign material from the groove portions **33** into the case **11**.

(3) At least part of the groove portions **33** has a groove width that narrows in the direction in which the first fixed terminal **19** is coupled to the case **11**. With this structure, the entrance of each groove portion **33** is widened so that the corresponding first fixed terminal connection pin **19b** can be readily inserted into the groove portion **33**.

(4) The switch device **8** includes the restriction walls **40** respectively arranged at the inner sides of the groove portions **33** in the housing **9** to limit the entry of foreign material into the housing **9**. With this structure, the restriction walls **40** project at the inner sides of the groove portions **33** and limit the entry of foreign material from the groove portions **33** into the housing **9**.

(5) The switch device **8** includes the press-fitting mechanism **43** that temporarily fixes the first fixed terminal **19** to the housing **9** when the proximal ends **19c** of the first fixed terminal body **19a** are press-fitted to the press-fitting portions **44** formed in the groove portions **33**. With this structure, when the switch device **8** is assembled, the first fixed terminal **19** can be temporarily fixed to the housing **9** through press-fitting. This allows for easy positioning of the first fixed terminal **19** and facilitates assembling of the switch device **8**. With this structure, when the switch device **8** is assembled, the first fixed terminal **19** can be temporarily fixed to the housing **9** through press-fitting. This allows for easy positioning of the first fixed terminal **19** and facilitates assembly of the switch device **8**.

(6) The first fixed terminal body **19a** is C-shaped. The first fixed terminal connection pins **19b** are arranged at the two ends of the first fixed terminal body **19a**. The groove portions **33** are respectively formed in the two opposing side walls **13** of the housing **9**. This structure facilitates manufacturing of the switch device **8** including the first fixed terminal **19** having the first fixed terminal connection pins **19b** arranged at the two sides of the first fixed terminal body **19a**.

11

Other Embodiments

The present embodiment may be modified as follows. The present embodiment and the following modifications can be combined if the combined modifications remain technically consistent with each other.

The first fixed terminal **19** does not need to be separate from the cover **12**. Instead, the first fixed terminal **19** may be integrated with the cover **12**.

The first fixed terminal **19** does not need to include the connection pins at two sides. Instead, the first fixed terminal **19** may include the connection pin only at one side.

The first fixed terminal connection pins **19b** do not need to be substantially L-shaped. Instead, the first fixed terminal connection pins **19b** may be shaped to, for example, extend 15 sideward straight from the proximal end **19c**.

The proximal ends **19c** of the first fixed terminal **19** do not need to be press-fitted into the case **11**. Instead, other portions of the first fixed terminal **19** such as the body portion or the connection pins may be press-fitted into the 20 case **11**.

The fixed contact **53** of the second fixed terminal **20** may be a rivet that is a component separate from, for example, the base portion **54** of the second fixed terminal **20**.

The movable terminal **18** may be any member having the 25 snap action mechanism **23**.

The guide groove **37** (groove portion **33**) does not need to be narrowed. Instead, the guide groove **37** may be straight or have any other shape.

The groove portion **33** may include, for example, only the 30 guide groove **37**.

The groove portion **33** does not need to include the press-fitting portion **44**. That is, the press-fitting mechanism **43** may be omitted.

The projecting wall **39** may entirely cover the groove 35 portion **33**.

The restriction wall **40** does not need to be arranged in the case **11**. Instead, the restriction wall **40** may be arranged on the cover **12**.

The height of the restriction wall **40** may be changed.

The cover **12** may be divided into segments with one of the segments structured to position the first fixed terminal **19**.

The movable terminal **18**, the first fixed terminal **19**, and the second fixed terminal **20** may be formed from a single 45 metal plate through pressing or the like.

The contacts do not need to be mounted on the board **21** by planar mounting. Instead, the contacts may be mounted on the board **21** by through-hole mounting.

Application of the switch device **8** is not limited to the 50 electric parking brake. The switch device **8** may be applied to other devices or apparatuses.

The switch device **8** is not limited to an onboard device and may be used for other devices, apparatuses, or systems.

While the present disclosure is described with reference to 55 examples, the present disclosure is not limited to the example or the configuration of the example. The present disclosure includes various variations and modifications within an equivalent range. In addition, various combinations and forms and other combinations and forms, which include only one element or more, shall be within the scope or a range of ideas of the present disclosure.

Various changes in form and details may be made to the examples above without departing from the spirit and scope of the claims and their equivalents. The examples are for the 65 sake of description only, and not for purposes of limitation. Descriptions of features in each example are to be consid-

12

ered as being applicable to similar features or aspects in other examples. Suitable results may be achieved if sequences are performed in a different order, and/or if components in a described system, architecture, device, or circuit are combined differently, and/or replaced or supplemented by other components or their equivalents. The scope of the disclosure is not defined by the detailed description, but by the claims and their equivalents. All variations within the scope of the claims and their equivalents are included in the disclosure.

What is claimed is:

1. A switch device, comprising:
a movable terminal including a snap action mechanism that bends a spring when a user moves an operating portion;
a first fixed terminal that contacts the movable terminal when the spring is not bent;
a second fixed terminal that contacts the movable terminal when the operating portion is moved by a specified amount to bend the spring; and
a housing that accommodates at least the first fixed terminal, wherein:
the first fixed terminal includes

a first fixed terminal body that contacts the movable terminal, and
a first fixed terminal connection pin bent sideward from the first fixed terminal body and mounted on a board; and

the housing includes a groove portion that allows for passage of the first fixed terminal connection pin, wherein
the housing includes a case and a cover, the case including an opening, and the cover closing the opening and configured to position the first fixed terminal, and
the cover includes a projecting wall fitted into at least part of the groove portion when the cover is coupled to the case.

2. The switch device according to claim 1, wherein at least 40 part of the groove portion has a groove width that narrows in a direction in which the first fixed terminal is coupled to the case.

3. The switch device according to claim 1, further comprising:
a restriction wall arranged at an inner side of the groove portion in the housing and configured to limit entry of foreign material into the housing.

4. The switch device according to claim 1, further comprising:

a press-fitting mechanism that temporarily fixes the first fixed terminal to the housing when a proximal end of the first fixed terminal body is press-fitted to a press-fitting portion formed in the groove portion.

5. A switch device, comprising:
a movable terminal including a snap action mechanism that bends a spring when a user moves an operating portion;
a first fixed terminal that contacts the movable terminal when the spring is not bent;
a second fixed terminal that contacts the movable terminal when the operating portion is moved by a specified amount to bend the spring; and
a housing that accommodates at least the first fixed terminal, wherein:
the first fixed terminal includes

a first fixed terminal body that contacts the movable terminal, and

a first fixed terminal connection pin bent sideward from the first fixed terminal body and mounted on a board; and the housing includes a groove portion that allows for passage of the first fixed terminal connection pin, 5 the first fixed terminal body is C-shaped, the first fixed terminal connection pin is one of two first fixed terminal connection pins respectively arranged at two ends of the first fixed terminal body, and the groove portion is one of two groove portions respectively 10 formed in two opposing side walls of the housing.
